UNITED STATES PATENT OFFICE.

PHILIP FRANCIS ODDIE, OF OSCHERSLEBEN, NEAR MAGDEBURG, GERMANY.

PRESSURE-REGULATING DEVICE FOR COMPENSATORS OF DIRECT-ACTING PUMPS.

SPECIFICATION forming part of Letters Patent No. 721,075, dated February 17, 1903.

Application filed February 11, 1902. Serial No. 93,597. (No model.)

To all whom it may concern:

Be it known that I, PHILIP FRANCIS ODDIE, civil engineer, a subject of the King of Great Britain and Ireland, residing at Oschersleben, 5 near Magdeburg, Germany, have invented new and useful Improvements in or Relating to Pressure-Regulating Devices for Compensators of Direct-Acting Pumps, of which the following is a specification.

- 10 My invention relates to pressure-regulating devices for compensators of direct-acting pumps, and has for its chief object to provide a regulation of the pressure of the working fluid in the compensator-cylinders of direct- 15 acting pumps. In such pumps as hitherto constructed when the compensator-pressure is too great the pump makes too long a stroke, and, on the other hand, should the pressure be too small the pump makes too short a stroke. 20 The proper pressure required in the compensator cylinder or cylinders of such pumps varies with the steam-pressure, the water-pressure, and also with the speed, so that an ordinary spring or constantly-loaded safety-valve 25 will not meet the requirements of these varying conditions.

According to my invention a valve is provided the action of which depends on the length of stroke of the pump—that is to say, 30 the valve only acts after the pump-pistons have exceeded the normal length of stroke and remains inactive should the pistons make too short a stroke. One form of carrying out this is shown in the accompanying drawings, 35 in which the valve-casing is connected with the air-pressure reservoir of the compensator, and in which—

Figure 1 is a side elevation, partly in section; and Fig. 2 a detail view of the non-return 40 turn valve shown in Fig. 1.

s is the steam-cylinder, the piston of which is connected by a rod *r* with the cross-head *t*. To the other end of the latter the piston-rod *d* of the pump-cylinder (not shown) is attached. 45

e designates the compensating or equalizing cylinder, being arranged at right angles to the pump and steam cylinders and in which works the compensating piston or plunger *f*.

50 *g* and *h* are links or levers pivoted together at *i*.

The lower end of the lower lever *h* is guided

by a lateral rod *k* and rests freely upon the equalizing-piston *f* without being connected thereto. The two levers *g* and *h* are pivoted together by means of a bolt *i*, upon which is rotatably mounted a roller *l*, which can slide in a slot *m* in the cross-head *t*. 55

The space beneath the equalizing-plunger *f* is connected through a conduit *n* with an air-chamber *o*. The air is maintained under constant pressure by means of a small air-pump *p*, driven, say, by the lateral guide-rod *k*, previously mentioned. The power acting in the first half of the stroke upon the equalizing-plunger is given back to the engine during the second half of the stroke when the pressure acting upon the steam-piston is reduced in consequence of the expansion of the working fluid. 60 65

In connection with the air-chamber *o* is a non-return valve *2*, mounted in a casing *1* and opening inward. It is provided with a spindle *3* and cap *4*. A spring *5* presses on this cap *4* and tends to keep the valve closed. 70 75

In the constructional form shown a lever *a* is provided, rotatably mounted at *b* on the casing, one end of which is so arranged and attached by means of a link *c* to some reciprocating part of the pump, preferably to the guide-rod *k*, that it reproduces on a suitably-reduced scale the motion of the pump-piston. The other end of the lever is provided with a set-screw *6*, which can be adjusted so that when the pump is making its proper or normal stroke its point just touches the cap *4*. If, however, for any reason the pump should make a slightly-longer stroke, the point of the set-screw will press on the cap *4* and the valve *2* will be opened and the pressure relieved. 80 85 90 This action will be repeated also at the end of the following stroke should the pressure continue to be too great until the stroke has again become normal.

As mentioned, a small air pump or compressor *p* is used, so as to make up for the loss of air. This air-pump, which is provided with the inlet-valve *p'*, works constantly with the main pump and forces air into the chamber *o* through the communicating valve *p*. The pressure of the air therefore constantly increases until the full stroke is reached, while further increase is prevented by the action of the valve, as before described. 95 100

The invention is not limited to the type of pump above described, as it may be applied to pumps of the oscillating-cylinder type or to other types for compensator-pumps.

5 While I have shown my invention as embodied in but one form, it will be understood that I do not so limit myself, as many modifications and changes might suggest themselves to those skilled in the art, which modifications could be made without departing from the spirit of my said invention.

Having thus described my said invention, what I claim, and desire to secure by Letters Patent of the United States, is—

15 1. In a pressure-regulating mechanism for direct-acting pumps, the combination with the steam and pump cylinders, pistons and piston-rod connecting the same; of a compensator-cylinder disposed at right angles to said cylinders, a piston therein, connecting means interposed between said piston-rod and compensator-piston, means for exerting a pressure behind said compensator-piston, and means operated by said compensator-piston for relieving said pressure when the stroke of said piston-rod exceeds certain limits.

20 2. In a pressure-regulating mechanism for direct-acting pumps, the combination with the steam and pump cylinders, pistons and piston-rod connecting the same; of a compensator-cylinder disposed at right angles to said cylinders, a piston therein, connecting means interposed between said piston-rod and compensator-piston, a pump operated by 25 said piston-rod for exerting a pressure behind said compensator-piston, and means for relieving said pressure when the stroke of said piston-rod exceeds certain limits.

25 3. In a pressure-regulating mechanism for compensators of direct-acting pumps, the combination with the steam and pump cylinders, pistons and a piston-rod connecting the same; of a compensator-cylinder disposed at right angles to said cylinders, a piston in 30 said compensator-cylinder, an air-chamber having communication with said compensator-cylinder, connecting means interposed between said piston-rod and compensator-piston, means for normally maintaining a pressure in said air-chamber, and means operated by said compensator-piston for automatically relieving the pressure in said air-chamber when the stroke of said piston-rod exceeds certain limits.

40 4. In compensating mechanism for direct-acting pumps, the combination with the steam and pump cylinders, pistons and a piston-rod connecting the same; of a compensator-cylinder located at right angles to said cylinders, a piston therein, a toggle-lever having one end held stationary and its central jointed portion adapted to be acted upon by said piston-rod, a link having one end stationary and its free end connected to the lower end of said toggle-lever resting upon said compensator-piston, an air-chamber having communication with said compensator-cylinder, means for normally maintaining a pressure in said air-chamber, and means for relieving the pressure in said air-chamber when the stroke of said piston exceeds predetermined limits.

45 normally maintaining a pressure in said air-chamber, and means for relieving the pressure in said air-chamber when the stroke of said piston exceeds predetermined limits.

5. In compensating mechanism for direct-acting pumps, the combination with the steam and pump cylinders, pistons and a piston-rod connecting the same; of a compensator-cylinder located at right angles to said cylinders, a piston therein, a toggle-lever having one end held stationary and its central jointed portion adapted to be acted upon by said piston-rod, a link having one end stationary and its free end connected to the lower end of said toggle-lever resting upon said compensator-piston, an air-chamber having communication with said compensator-cylinder, a pump operated by said link for normally maintaining a pressure in said air-chamber, and means for relieving the pressure in said air-chamber when the stroke of said piston exceeds predetermined limits.

6. In compensating mechanism for direct-acting pumps, the combination with the steam and pump cylinders, pistons and a piston-rod connecting the same; of a compensator-cylinder located at right angles to said cylinders, a piston therein, a toggle-lever having one end held stationary and its central jointed portion adapted to be acted upon by said piston-rod, a link having one end stationary and its free end connected to the lower end of said toggle-lever resting upon said compensator-piston, an air-chamber having communication with said compensator-cylinder, means for normally maintaining a pressure in said air-chamber, and a relief-valve operated by said link for relieving the pressure in said air-chamber when the stroke of said piston exceeds predetermined limits.

7. In compensating mechanism for direct-acting pumps, the combination with the steam and pump cylinders, pistons and a piston-rod connecting the same; of a compensator-cylinder located at right angles to said cylinders, a piston therein, a toggle-lever having one end held stationary and its central jointed portion adapted to be acted upon by said piston-rod, a link having one end stationary and its free end connected to the lower end of said toggle-lever resting upon said compensator-piston, an air-chamber having communication with said compensator-cylinder, a pump operated by said link for normally maintaining a pressure in said air-chamber, and a relief-valve operated by said link for relieving the pressure in said air-chamber when the stroke of said piston exceeds predetermined limits.

8. In compensating mechanism for direct-acting pumps, the combination with the steam and pump cylinders, pistons and a piston-rod connecting the same; of a compensator-cylinder disposed at right angles to said cylinders, a piston therein connecting means interposed between said piston-rod and compensator-piston, an air-chamber having communication with said compensator-cylinder, means for normally maintaining a pressure in said air-chamber, and means for relieving the pressure in said air-chamber when the stroke of said piston exceeds predetermined limits.

inder, a pivoted link having its free end connected to said connecting means, a pump operated by said link for normally maintaining a pressure in said air-chamber, a relief-valve 5 connected to said air-chamber, means carried by said valve for normally retaining the same closed, a pivoted lever carrying an adjustable set-screw adapted to bear upon said valve, and a connection interposed between 10 said pivoted lever and said link, whereby

said valve will be automatically opened when the stroke of said piston-rod exceeds a certain limit.

In testimony whereof I have signed my name to this specification in the presence of 15 two subscribing witnesses.

PHILIP FRANCIS ODDIE.
